UNITED STATES PATENT OFFICE.

HENRY A. WISE WOOD, OF NEW YORK, N. Y., ASSIGNOR, BY MESNE ASSIGNMENTS, TO WOOD NEWSPAPER MACHINERY CORPORATION, OF NEW YORK, N. Y., A CORPORATION OF VIRGINIA.

MOLD FOR STEREOTYPING AND MEANS FOR SUPPLYING METAL THERETO.

1,266,740.

Specification of Letters Patent. Patented May 21, 1918.

Application filed September 16, 1913, Serial No. 790,071. Renewed October 12, 1917. Serial No. 196,346.

To all whom it may concern:

Be it known that I, HENRY A. WISE Wood, a citizen of the United States, residing at New York, in the county of New York and State of New York, have invented a new and useful Mold for Stereotyping and Means for Supplying Metal Thereto, of which the following is a specification.

This invention relates to a stereotyping apparatus, particularly of that kind in which the parts are operated by power such, for example, as shown in my application, Serial Number 726,239, filed October 17, 1912.

The principal objects of the invention are to provide a construction for this purpose in which the motion of the mold back away from casting position will automatically render the pump inoperative for delivering metal; and improved means coöperating therewith for delivering casting plates, discarded tails and pigs of metal into the melting pot.

The invention also involves improvements in the details of construction of these various parts as will appear hereinafter.

Reference is to be had to the accompanying drawings in which—

Figure 1 is a side elevation of a portion of a stereotype casting and finishing apparatus, showing the application of a preferred embodiment of this invention thereto.

Fig. 2 is an end view of the same with the melting pot in section to show interior construction;

Fig. 3 is a plan of the mechanism for operating the parts.

Fig. 4 is a side view of certain parts of the apparatus with portions shown in section.

Fig. 5 is a sectional view on a large scale on the line 5—5 of Fig. 4.

Fig. 6 is an end view of the portion of the mechanism for feeding metal to the melting pot; and

Fig. 7 is a sectional view on the line 7—7 thereof.

The invention is shown as applied to a stereotype plate casting machine like that shown in my co-pending application for patent on a machine for casting and delivering curved stereotype printing plates, filed on the 16th day of September, 1913, Serial No. 790,070.

Referring first to Figs. 1 and 2, it will

be seen that a frame 10 is shown on which is a vertical upright core 11, and a movable segmental back 12. This back is connected by a link 13 with a toggle yoke 14, fixed on a shaft 15. The link and toggle yoke are pivoted together to form a true toggle lever and means comprising links 16 and a cam 17 are shown for drawing down the central joint of the toggle and moving the back away from the core. The frame is provided with an eccentric bushing 20 in which the shaft 15 is loosely mounted. This shaft can be adjusted by turning the bushing by means of adjusting screws 21.

On this shaft is a cam 22 operating a roll 23 which is loosely mounted on a rod 24 connected by a bell crank 25 with a swivel 70 puppet 26. This puppet is mounted between collars 36 on a valve rod 27. A valve 28 on the bottom of this rod is arranged to open and close a port 29, in a cylinder 30 in the melting pot 31. The opening of this valve 75 prevents effective operation of the pump as I have previously shown in my Patent No. 1,009,206. It will be seen, therefore, that as the back starts to move away from the core, this valve will be opened, and consequently, 80 the piston 32 in the cylinder 30 can continue to operate without forcing any metal through the nozzle 33. It simply causes it to circulate through the port 29.

For the purpose of operating the parts a 85 motor 40 is shown operating a main shaft 41 in any desired way. This shaft in turn operates a cam shaft 42 on which is the cam 17 for operating the links 16, and consequently, the cam 22.

Also connected with the main shaft 41, I have shown a shaft 44 provided with a handle 45 for rotating the parts by hand and a shaft 46 connected to operate a shaft 47 having right and left worms 48 thereon to 95 operate the elevator as will appear herein-after.

On the cam shaft 42 is a cam 50 which operates a cam roll 51. This roll is mounted on one arm of a two-branched lever 52 which is pivoted to swing loosely on a shaft 53 supported by the frame. The other arm of this lever is connected by a stud 54 with an arm 55 also pivoted loosely on the shaft 53 and pivotally connected by a link 56 with 100 a nut 57 which is movably mounted on a

lever 58. This lever is keyed to the end of a shaft 59 and the nut 57 is adjustably connected with the lever by means of a screw 62 which engages the nut and is mounted on the lever radially with respect to the shaft. It will be obvious that the extent of motion imparted to the lever by the cam 50 will depend upon the adjustment of the nut 57 on the screw 62. This adjustment is made by means of a hand wheel 63 having a sprocket 64 thereon. This sprocket operates a chain 65 which by means of other sprocket and chain connections operates a sprocket wheel 61 fixed to the screw 62. The hand wheel 63 is in a convenient place for manipulation by the operator to adjust the throw of the lever 58.

On the shaft 59 is an arm 70 which by a link 71 is connected with a piston rod 72 to the bottom of which is secured the piston 32. It will be obvious, therefore, that the operation of the hand wheel 63 adjusts the length of the stroke of this piston so that a full charge of metal can be pumped into the mold when the level of metal in the pump is low. The pump is shown as provided with a mixer 73 operated by a motor 74 or in any other desired manner.

For the purpose of feeding the metal to the melting pot the following mechanism is provided. On the frame is a chute 80 for receiving the tails T, which are severed from the plates by the finishing mechanism (not shown). These tails T slide down this chute in the position indicated at the top of Fig. 6.

One advance corner of each one engages a projection 81 on one lower side of the chute. This causes the tail to be turned around a quarter of a turn so that one of the straight edges is foremost. Then in this position it slides down an incline 82 which forms a part of the chute and which is at an angle to the chute 80, so as to be less abrupt. At the bottom of this incline one advance corner engages a projection 83 on the same side. This causes it to turn again so that one of its curved edges is foremost. Then it slides by gravity over an incline 84 into a conveyer for elevating it into the melting pot. It is stopped by a fixed plate 88.

The conveyer is shown as located in an inclined casing 85 provided with two separate bottoms 86 in the plane of the incline 84.

The conveyer comprises two endless chains 87 which are operated by the two worms 48 and worm wheels 98. The outer strands of the chains pass upwardly on the outsides 60 of the bottoms 86 and the inner strands pass downwardly between these bottoms.

The two chains are provided with projections 89, kept in registration and so arranged that two of these projections pass 65 upwardly on the outer strands together.

Therefore, they engage the two edges of the plate and cause the plate to travel upwardly to the top of the conveyer by which it is dumped over into the melting pot. The chains pass over sprocket wheels 90 and 90^a, those at the top located over the melting pot.

The projections on the inner strands of the chains coming down at the center do not interfere with the ascent of the tail as they come within its concavity. It will be understood, of course, that these chains can be used to elevate used plates placed in them by hand and in practice the chains are run at such a speed that these plates can be put in alternately with the tails.

For the purpose of elevating pigs of metal, the casing is provided with a longitudinal projection 91 along one side of the bottom. This forms with the side wall of the casing, a passage way along which the pigs are elevated by one chain.

Although I have illustrated and described only a single embodiment of the invention, I am aware of the fact that many modifications can be made therein by any person skilled in the art without departing from the scope of the invention as expressed in the claims, therefore I do not wish to be limited to all the details of construction herein shown and described, but what I do claim is:—

1. The combination with a movable mold section and means for moving it, of a pump for supplying metal to the mold having a piston, means for operating the piston, a cam operated by said mold section moving means, and positive means operated by said cam for rendering said pump inoperative independently of the operation of the piston.

2. The combination with a movable mold section and a toggle for operating it, of a shaft fixed to and oscillatable with said toggle, a pump cylinder, means for controlling the operativeness of said pump cylinder to deliver metal, and means operated by said shaft for operating the first named means.

3. The combination with a movable mold section, of a lever for operating it, a shaft fixed to said lever about the axis of which the lever turns with the shaft, a cam on the shaft, a pump for supplying metal to the mold, and means operated by said cam for rendering said pump inoperative when the mold section and lever are moved from casting position.

4. The combination with a movable mold section and a lever for operating it, of a shaft, means operated by said shaft for operating said lever, a cam fixed with respect to said lever and adapted to be turned when the lever is turned to move the mold section, a pump having a piston, means for operating the piston, a cylinder for the piston having a port, a valve for said cylinder arranged to open and close the port, and means op-

erated by said cam for controlling the position of said valve.

5. The combination with a mold having a movable member, a pump for supplying metal to the mold having a melting pot, and an elevator for supplying metal to the melting pot, of a motor, a main shaft driven by the motor, means connected with said main shaft for operating the movable mold member, means connected with the main shaft for operating the pump, and means connected with the main shaft for operating the elevator.

10 6. The combination of a main shaft, a cam shaft connected therewith and operated

thereby, a pump, a cam on said shaft, connections from the cam to the pump for operating the pump, a mold in position to be supplied by metal from said pump, said mold having a movable element, a toggle lever for operating said movable element, and a system of levers operated by said shaft for operating said toggle lever.

15 In testimony whereof I have hereunto set my hand in the presence of two subscribing witnesses.

HENRY A. WISE WOOD.
